UNITED STATES PATENT OFFICE.

FRANK F. ERNST AND WILLIAM H. GORMAN, OF LEOMINSTER, MASSACHUSETTS,
ASSIGNORS TO YALE NOVELTY COMPANY, OF LEOMINSTER, MASSACHUSETTS,
A CORPORATION OF MASSACHUSETTS.

DESIGN FOR A DOLL'S HEAD.

56,588.

Specification for Design.

Patented Nov. 16, 1920.

Application filed May 14, 1919. Serial No. 297,144. Term of patent 3½ years.

To all whom it may concern:

Be it known that we, FRANK F. ERNST and WILLIAM H. GORMAN, citizens of the United States, both residing at Leominster, in the county of Worcester and State of Massachusetts, have invented a new, original, and ornamental Design for a Doll's Head, of which the following is a specification, reference being had to the accompanying drawing, forming part of this specification, in which—

Figure 1 is a front view of a doll's head showing our design;

Fig. 2 is a side view, and

Fig. 3 is a rear view.

I claim:

The ornamental design for a doll's head as shown.

In testimony whereof we have hereunto affixed our signatures.

FRANK F. ERNST.

WILLIAM H. GORMAN.
